SOCKET MEMBER FOR COAXIAL CONNECTORS

Kenneth McGee, Dayton, and Harold D. Vanderpool, Springfield, Ohio

Application July 4, 1945, Serial No. 603,243

4 Claims. (Cl. 173—328)

(Granted under the act of March 3, 1883, as amended April 30, 1928; 370 O. G. 757)

1

The invention described herein may be manufactured and used by or for the Government for governmental purposes, without the payment to us of any royalty thereon.

The invention to be hereinafter described relates to coaxial connectors of the pin and socket type.

In present connectors of this type, where a coaxial line is involved, there are a number of serious objections and difficulties. With coaxial lines a common practice is to connect the usual outer flexible braid conductor to a stationary and relatively fixed tubular conductor element. The braid formation is decidedly extensible. The other or center conductor of the coaxial line, usually a rigid member such as a rod or tube, bared for a short distance, is connected, in well known manner, to a male pin or to a female socket. In assembling to complete the circuits there has been frequent difficulty in completing connection to the center conductor. As a connector is coupled and circuit through the braid completed, the pin-and-socket elements for connecting the center conductor frequently do not cooperate as intended. Instead of the pin slipping into the socket so as to make a good electrical connection, the slight frictional resistance between the pin and socket is not overcome which results in the center conductor of the coaxial line being forced lengthwise back within the outer braid. In such cases the only electrical contact is at the contacting extremities of said pin and socket and there is nothing to retain them in such relation so as to maintain or continue such contact. As a result, in the connectors heretofore known, the connection of the center conductor is frequently incomplete, inadequate, and unreliable and, at times, wholly non-existent.

A further serious objection is that, in making such connections, according to known practices, a considerable portion of the end of the center conductor must be bared or stripped of its insulation.

The main objects of the present invention are to overcome the above and other defects and disadvantages and provide a simple, efficient, compact and durable connector of the type stated, in which there will be, at all times, adequate and efficient electrical contact between cooperating members in the circuit of the center conductor, while also completely shielding the cooperating elements in said circuit of the center conductor against radio noise, both as to reception and as to transmission.

In order to more clearly disclose the construction, operations and use of the invention, reference should be had to the accompanying drawings forming part of the present application. The drawings have been made on a much en-

larged scale in order to more clearly and adequately illustrate the details of the several parts. Throughout the several figures of the drawings, like reference characters designate the same parts in the different views.

In the drawings:

Fig. 1 is a central, longitudinal cross section through the female member of a connector adapted to join two lengths of coaxial cable; and

Fig. 2 is a like view through the cooperating male member.

For clearness, the usual outer metal shells, for the phenolic or similar inserts, have been omitted from the drawing as they form no part of the present invention.

Of the two cooperating members the socket or female member (Fig. 1) will first be described and then the corresponding pin or male member (Fig. 2).

A usual block or body 1 of phenolic or other insulating material, generally of cylindrical configuration, is provided. It is provided with a longitudinally disposed bore 2 which may be of any desired cross sectional outline or configuration, circular being preferred. One end of this bore (as the right end of Fig. 1) may be of slightly increased diameter relatively to the remainder. The opposite end (the left end in Fig. 1) is provided with a circumferential abutment extending radially inwardly. This abutment along its inner circumference provides a stop shoulder 4 and a deflecting, circumferential incline or funnel wall or surface 5 leading into the free end of said bore 2.

Within the bore 2 is snugly seated, either removably or in fixed relation, a tubular conducting sleeve 6. In assembled relation, this tube extends approximately from shoulder 4 to a short distance beyond the inner end of the enlarged portion of bore 2. Up to the enlarged portion of bore 2 in assembled positions, sleeve 6 has the same outside diameter as the inside diameter of bore 2. Its radial thickness is approximately the radial width of stop shoulder 4.

Within the outer enlarged portion of bore 2 is disposed a cup shaped cap member 7 provided with a terminal internally threaded portion 8. The end of bore 6 extending into the enlargement of bore 2 is externally threaded as at 9 to cooperate with the threaded portion 8. While the outside diameter of cap 7 is equal to the inside diameter of the enlarged portion of bore 2 for a part of its length, that outside diameter does not continue throughout the entire length of the cap. That enlarged diameter extends only a distance equal to that of the length of the enlarged part of bore 2. From that point on to the outer or closed end of the cap 7, the outside diameter of the cap is reduced. As shown in Fig. 1, this reduction is to approximately the maximum outside diameter

60

of sleeve 6, providing an abrupt shoulder 10 which, when the parts are fully assembled, will be flush with and in the same plane as the adjacent end of block 1. This two-part construction of tube and cap, or an equivalent construction or arrangement is desirable for practical and ready assembly in quantity production as will more clearly appear hereinafter.

The outer or exposed end of cap 7 is provided with a short tubular collar 11 concentric with the cap and, in assembled relation, concentric with the tube 6. In use, this collar 11 will have approximately the same inside diameter as the outside diameter of the insulated center conductor of the coaxial cable with which it is to be used.

Within the assembled cap 7 and sleeve 6 is disposed a socket or female tubular contact member 12. It has the usual spring or resilient fingers 13. Its opposite end is cored out longitudinally to form a bore 14, of slightly greater diameter than that of the center conductor 17 of the coaxial cable with which it is to be used, such bore being provided to receive the said center conductor of the cable. The inner or remote end of bore 14 is closed off by a web, wall or partition 15. Slightly beyond that partition 15 a radial opening 16, leading into the bore 14, is provided for soldering. In use, the bared end section of the center conductor 17 of the coaxial cable is seated in bore 14 and soldered therein and thereto by solder 18 applied through the radial opening 16. The tubular member 12 is securely and permanently anchored within the cap 7 and adjacent end of the sleeve 6 by a body of insulating cement 19. By so anchoring the member 12, it is impossible for that member to move relatively to sleeve 6. By soldering or otherwise securely anchoring the center conductor 17 to the anchored member 12, it becomes impossible for that end of the center conductor 17 to move relatively to any of the parts 6, 7 or 12.

In assembling, the end of the outer flexible braid 20 of the coaxial cable is secured in any suitable manner, as by soldering to the tubular collar 11. In this way, the coaxial cable end has both the center and the outer conductors 17, 20 fixed or positively anchored relatively to each other, absolutely preventing retraction of the end of the center conductor.

A head slab 21 of the same general type of material as block 1 cooperates with block 1. These two parts, block 1 and slab 21, are substantially the same as in conventional equipment. Slab 21 is provided with a centrally disposed bore 22 adapted to be concentrically aligned with bore 2, bore 22 being of the same diameter as the outside diameter of that part of cap 7 extending through slab 21. Accordingly, when assembled, slab 21 will engage shoulder 10 on cap 7, retaining the assembly within block 1 and slab 21. The slab 21 is held in operative position against block 1 by any suitable means, as by a conventional case or shell and spring washer which, as previously stated, have been omitted from the drawing for clearness.

Cooperating with the socket or female member, just described, is the corresponding male connector member. In general, the construction, arrangement and disposition of the various parts of this unit are very similar to those of said socket member.

The pin or male member comprises a block or body 100 of insulating material of the same general type as that of block 1. It is provided with a bore 102 of substantially the same diameter as

bore 2 to receive a cylindrical conducting tube 101 of substantially the same outside diameter as tube 6. The sleeve 101 is only partially embedded in block 100. The free end portion extending beyond block 100 is split, in well known manner, to provide deflectable resilient spring fingers 103. Fingers 103 are provided with centering, guiding and contact lugs 104. As a means of adequately anchoring tube 101 in bore 102, the tube is provided with a circumferential outwardly directed rib or shoulder 105 adapted to be seated in the enlarged end of bore 102. When properly assembled, shoulder 105 will be flush with the face of block 100. Tube 101, instead of being a separate piece from its cooperating cap is shown as integral therewith. As in the socket member, a head block 106 is provided. This head block is provided with a centrally disposed bore of the same inside diameter as the outside diameter of the body of tube 101 and adapted to be concentrically aligned with bore 102. Head block 106, when assembled, may be maintained in operative position against block 100 by its casing or shell in the same way as slab 21 is maintained relatively to block 1. In that position, head block 106 engages shoulder 105 and locks tube 101 in position. Tube 101 is formed with a tubular extension or collar 107 concentrically disposed relatively to tube 101. This collar 107 is provided as a suitable means for connecting the braided outer conductor of the coaxial cable to the conducting tube 101.

Concentrically within tube 101 is anchored, by means of a body of cement 110 or other insulating material, a pin or male contact member 108. This is a tube of small diameter having a bore of substantially the same inside diameter as the outside diameter of the center conductor of the coaxial cable with which the present connector is designed to be used. The cement 110 is hollowed out, adjacent the collar 107, to receive the dielectric sheath of a coaxial cable.

In assembling, a length of the end of the center conductor is bared and slipped into the tube 108, taking care that the dielectric sheath of the coaxial line is completely seated in the socket previously formed in the insulating material 110. The extremities of the tube 108 and the center conductor within it are then soldered together at 109.

In this pin member, as in the socket member, the center conductor of the coaxial cable is positively anchored in fixed position and can not possibly move or be retracted relatively to the outer braid. The outer braid is soldered in usual manner to collar 107.

In both members sleeve 6 and tube 101, respectively provide complete shielding for those portions of the center conductors which extend beyond the dielectric and outer flexible conductors of the coaxial cables.

While, in quantity production, there may be various ways and methods of manufacture and assembly, according to circumstances and the individual preferences or inclinations of the respective manufacturer or producer, one thoroughly acceptable way is along the following lines. For the socket member, bare the requisite length of the center conductor 17, slip the bared portion through the collar 11 with the braid overlapping the collar and secure the braid 20 to the collar. This operation, at the same time, inserts the center conductor into the end of the socket member 12. Now solder the center conductor at 16. The insulating compound 19 anchors member 12 in place. Then assemble cap 7 and sleeve 6 by

threading them together. Slip this assembly into the bore 2 to the point where the shoulder 10 lies flush with the face of block 1. The inner end of sleeve 6 will then fall just within the radial abutment 3. Finally, assemble the slab 21 and body 1, overlapping 10 and apply the standard shell or casing in the well known manner. That completes the socket unit.

The pin or male unit is assembled in substantially the same way, the difference being that the tube 101, shoulder 105 and collar 107 may be made integrally, as the solder 109 is applied at the outer end of the tubular pin or male contact member 108 at a point beyond the open end of tube 101. Accordingly, the step of assembling tube and collar is not involved.

In completing the circuits or electrical contacts, the pin member is plugged into the socket member. In this operation the lugs 104 of the fingers 103 as they engage the tapered surface 5 of abutment 3, flex fingers 103 inwardly far enough to pass abutment 3. Resilience of fingers 103 maintains contact between lugs 104 and conductor sleeve 6. Continued inward movement carries the pin member 108 longitudinally within the resilient fingers 13 of the tubular member 12. Resilience of fingers 13 maintains contact with the pin member 108. It will be understood that the rounded soldered end 109 of the pin member 108 facilitates this assembly between elements 12 and 108. It hardly need be stated that the parts are so proportioned that, when assembled, blocks 1 and 100 are actually or approximately in contact, the whole free length of parts 101 and 108, extending beyond block 100 lying, respectively, within sleeve 6 and fingers 13 of tube 12.

From the above it will be obvious that the center conductor, heretofore loose relatively to the outer braid, by this invention has been securely anchored or fixed in its relation to the braid and can not be retracted by any action in assembling the pin within its socket.

It is thought that the construction, operation and use of the invention will be clear from the preceding detailed description.

Changes may be made in the construction, arrangement and disposition of the various parts of the invention within the scope of the appended claims without departing from the field of the invention and it is meant to include all such within this application wherein only one preferred construction and arrangement has been illustrated, purely by way of example and with no thought or intent to, in any degree, limit the invention thereby.

Having thus described our invention, what we claim and desire to protect by Letters Patent is:

1. A connector member for a coaxial cable of the type comprising an internal conductor, a tubular dielectric surrounding said conductor, and a flexible external conductor surrounding said dielectric, said connector member comprising: an outer block of dielectric material, an outer tubular conductor mounted in said block and provided intermediate its ends with an external projection which extends into said block to lock the outer tubular conductor against forward longitudinal movement relative to the block, said external projection also forming a shoulder which is flush with the rear surface of said block, a head slab of dielectric material fitted about the outer tubular conductor with its forward face abutting said shoulder and said rear surface of the insu-

lating block to lock the outer tubular conductor against rearward longitudinal movement relative to the block, the tubular conductor extending rearward through the head slab and formed with a tubular collar of reduced diameter at its rear end, the external conductor of said cable extending over said collar and secured thereto, the internal conductor and tubular dielectric of the coaxial cable extending forward through said collar and into said outer tubular conductor, said internal conductor being bared forward of the collar, an adherent mass of dielectric material fixedly positioning said bared internal conductor within said outer tubular conductor, and an inner tubular conductor fixedly secured within said outer tubular conductor by said adherent dielectric mass, the forward end of said bared internal conductor of the coaxial cable being electrically and mechanically connected to said inner tubular conductor.

2. Structure as in claim 1 further characterized in that the outer dielectric block fits snugly about the outer tubular conductor throughout the extent thereof forward of said shoulder, the outer block extending slightly beyond the forward end of the outer tubular conductor, the front surface of said block being beveled adjacent the front end of the outer tubular conductor to provide a sloping surface leading into the outer tubular conductor, and the inner tubular conductor being formed with a plurality of spring fingers which extend forward beyond its connection to the inner tubular conductor.

3. Structure as in claim 1 further characterized in that the outer tubular member extends forward beyond the outer dielectric block to form a plurality of spring fingers, a peripheral external projection formed at the forward end of said fingers, said inner tubular conductor extending forward beyond said spring fingers.

4. In an electrical connector, a dielectric sleeve formed with a longitudinal bore extending therethrough, an outer tube closely fitting within said bore, said tube being comprised of detachable elements, one of which extends rearwardly beyond said dielectric sleeve so as to be manually accessible, an electrical conductor extending through the rear extension into said tube, an adherent mass of dielectric material within said tube adjacent the rear tube extension fixedly securing said conductor within said tube, an inner tubular conductor fixedly secured to said adherent mass and extending forward thereof within the tube, said inner tubular conductor surrounding the forward end of said conductor and being electrically and mechanically connected thereto.
